LOOSE-LEAF BINDER

Elmer E. Harper, deceased, late of Monrovia, Calif.; by Esther Pardee Harper executrix, Monrovia, Calif.

Application July 16, 1945, Serial No. 605,386

2 Claims. (Cl. 129—35)

1

The present invention relates to loose-leaf binder devices, and aims to simplify very materially the construction of loose-leaf holders of this class and to provide a correspondingly inexpensive construction which will at the same time be more convenient for use as well as adapted for a wider range of use than most of the conventional forms of binder construction.

For this purpose the present invention comprises a holder providing space for the insertion and assembly of the margins of the loose leaf material, and efficient clamping elements for securing said margins in place and adapted to be retained in clamping position by being compressed within the space inside the holder.

In the carrying out of the invention the holder is constructed in channel form to provide a channel shaped receiving space of a length corresponding to the size of the sheets of loose leaf material having their marginal portions clamped therein, and the clamping elements are secured by being pressed between said sheets of material and one of the walls of said channel space.

The invention further comprises the use of curved spring clamping elements so arranged as to facilitate the assembly of the loose leaf material as their marginal portions are inserted into binding position and before the clamping and securing action is carried out by forcing said curved spring elements into flattened clamping relation within the holder.

It is also sought to devise a practical holder or binder device which is adapted to be readily designed for clamping and holding engagement with either the sides or the ends of the sheets of loose leaf material, in equally efficient binder relation.

With the foregoing general objects in view, the invention will now be described by reference to the accompanying drawing, illustrating one practical form of construction for embodying the proposed improvements, after which those features and combinations deemed to be novel and patentable will be particularly set forth and claimed.

In the drawing—

Figure 1 is a plan view (with portions represented as broken away) illustrating a loose leaf binder construction embodying the present features of improvement, the dotted lines indicating the open or unclamping position of the spring clamping elements;

Figure 2 is a side edge view of the same, with dotted lines illustrating the open position of one of the clamping elements for permitting the removal or insertion of the loose leaf material;

2

Figure 3 is a transverse sectional view, representing a section taken on the line 3—3 of Figure 1;

Figure 4 is an enlarged detail sectional view, representing a section taken on the line 4—4 of Figure 1; and

Figure 5 is a fragmentary plan view (partly broken away) illustrating a modified type of clamping element.

Referring now to the accompanying drawing in detail, the holder part of the improved construction is illustrated as an elongated section of suitable sheet material of suitable stiffness or rigidity, such as metal or plastic material, shaped into channel form having the top wall 7 and bottom wall 8, connected by a flat longitudinal wall 10, thus providing a housing space 12 for receiving the margins of the sheets of paper 14 or the like to be bound, and adapted to be inserted within said space 12 into end-abutting relation with the inner face of the wall 10, as clearly illustrated in Figure 4. Preferably the ends of the housing space 12 are closed by turning in the ends of the holder, as indicated at 15 in Figure 2.

Curved leaf springs 16, are provided to serve as clamping elements by engaging the margins of the sheet material 14 and securing the same by clamping action within the holder space 12. Obviously these curved clamping springs 16 may be used singly or in multiples, as for example, in pairs as illustrated in the drawing, with one end of the spring pivotally attached—as indicated at 18—to the top wall 7 and its other end provided with a button 20 or thumb-engaging terminal adapted to swing into and out of a recess 22 in said upper wall 7, when necessary for inserting or removing sheets of the material 14. Each of the recesses 22 has one of its outer corners formed with a barblike projection 24 adapted for engagement with the side of the spring near its end for retaining the same in its operative or binding position, as clearly represented in Figures 1 and 4.

A sheet of relatively heavier material 25 may be employed to serve as a backing sheet for the sheets 14 and either attached or left unattached to the holder member, and this material 25 may of course be either stiff or flexible as preferred, and in some cases may be a continuous sheet extending both above and below the assembly of inserted sheets 14, as indicated in Figure 4.

For inserting the loose leaf material, the ends of the clamping springs 16 are simply depressed and swung outward from engagement with the

detents 24 and into open position as represented by the dotted lines in Figures 1 and 2; and it will be readily seen that the upwardly extending and curved contour of the springs, in their open position, provide an efficient guiding means for facilitating the insertion of the sheet material and directing the same into the holder space 12 for clamping engagement by the springs as the latter are swung back again within the holder and re-engaged with the detent bars 24. The spring elements 16 are of course simply operated by thumb pressure and a pushing movement, in both the clamping and unclamping action, as required for either inserting or removing the loose leaf material from the holder.

It will thus be seen that the improved device provides a very compact and extremely simple construction for the carrying out of the desired objects of the invention. The combined holder and means for clamping the sheets provides a maximum holding and binding capacity for the sheets or loose-leaf material, greatly exceeding that of the prevailing or conventional type of split-ring binder, and has the important advantage of eliminating any necessity for punching or otherwise mutilating the sheet margins. Moreover the sheets are securely held and the clamping and unclamping means is easily and quickly operated with a minimum of effort, simply by thumb pressure and the operation of one hand. The ease of inserting the sheets as facilitated by the guiding action of the open curved springs greatly enhances the utility of the improved holder, and such method of insertion safeguards the sheets also against the mutilation so commonly experienced with split rings and other forms of retaining devices for loose leaf material. Again, with the slim channel type of holder of the present construction, an especially compact arrangement is made possible by the use of flexible cover or backing material, thereby allowing the complete device with all its contents to be simply folded or rolled into a very compact form for pocket use.

Also as hereinbefore pointed out, the holder of the present construction is equally well adapted for application to either the ends of the sheets 14 or to the side margins thereof as indicated by dotted lines in Figure 5.

In Figure 5 is illustrated a slightly modified form of the clamping elements, for which a curved wire clamp element 16' may be used in lieu of the leaf spring types 16, such wire elements being

pivoted at 18 by the use of an attaching clip 19, and provided with a plain thumb-engaging terminal 20', as shown.

It will therefore be apparent that a very compact and practical as well as highly efficient arrangement and construction have been devised for the embodiment of the proposed improvements, and while one very serviceable form of such construction has been herein described and set forth, it is desired to reserve the right to make whatever changes or modifications thereof may properly be deemed to fall within the scope of the appended claims.

Having thus described the invention, what is claimed and desired to be secured by Letters Patent is:

1. A loose leaf binder construction comprising, an elongated channel shaped holder providing a clamping space for the margins of loose leaf material, a curved spring element pivoted within said clamping space to one side of the holder and having swinging movement out of said space into a position at substantially right angles to the holder to permit insertion or removal of the loose leaf material and provide guiding means of curved contour for facilitating said insertion of the loose leaf material and also having swinging movement into said space to be compressed by the holder into pressure retaining engagement with said material after the insertion thereof.
2. A loose leaf binder construction comprising, an elongated channel shaped holder providing a clamping space for the margins of loose leaf material, and curved spring elements mounted pivotally on said holder for movement into either a position outside said space or an operative clamping position within said clamping space for pressure clamping engagement with said loose leaf material, said holder being provided with recesses for access to the ends of said curved spring elements and having detent means for retaining said spring elements in operative clamping position.

45 ESTHER PARDEE HARPER.
Executrix of Estate of Elmer E. Harper, Deceased.
